BUCKET STEP FOR AN AERIAL LIFT BUCKET AND LINER

Louis J. Kachavos, New Boston, N.H., assignor to Plastic
Techniques, Inc., New Boston, N.H.

Filed May 23, 1974, Ser. No. 472,623

Term of patent 14 years

Int. Cl. D12—05

U.S. Cl. D54—1 A

FIG. 3

FIG. 1

FIG. 4

FIG. 2

FIG. 1 is a perspective view of a bucket step for an aerial lift bucket and liner showing my new design.

FIG. 2 is a front elevational view thereof.

FIG. 3 is a side elevational view thereof.

FIG. 4 is a perspective view thereof, shown in its environment with the aerial lift bucket in broken lines for illustrative purposes only.

I claim:

The ornamental design for a bucket step for an aerial lift bucket and liner, as shown.
